UNITED STATES PATENT OFFICE.

CHARLES E. KNAPP, OF BROOKLYN, NEW YORK.

MATTING AND CARPET BINDING.

SPECIFICATION forming part of Letters Patent No. 324,942, dated August 25, 1885.

Application filed November 17, 1884. (No model.)

To all whom it may concern:

Be it known that I, CHARLES E. KNAPP, of the city of Brooklyn, county of Kings, and State of New York, have invented a new and useful Binding for Carpets, Mats, Matting, and other Material for the Covering of Floors; and I do hereby declare the same to be described in the following specification and represented in the accompanying drawings, of which—

10 Figure 1 is the binding, showing its form and shape when ready to be attached to the matting or carpeting. Fig. 2 and E represent a metal cap to be used for the purpose of covering the ends of the binding to add strength and durability to the binding, and is to be attached to the binding by means of rivets. Fig. 3 shows the binding and cap attached to the matting or carpeting.

15 The binding is intended to keep the material to which it is attached from raveling, to preserve the shape of the end of the material, and to cause the same to lie smooth on the floor, and to keep the same from wearing out.

20 It consists of a thin oblong piece of rubber, solid on one side and open on the other, to admit the ends of the material to which it is to be attached. The flaps that diverge from the solid side of the binding and form the open side cover, when attached, the top and bottom 25 of the end of the material or the upper and lower side, to which they are attached. The flaps are corrugated or plain on the surface, and are attached to the carpet or matting by means of rivets.

30 In the drawings the top flap is represented by the letter A, and is to cover the end of the

matting or carpeting which is uppermost on the floor. B represents the solid side of the binding, and C represents the under flap of the binding, which covers the portion of the 40 material next to the floor. D represents the portion of the binding to be covered by the metal cap shown in Fig. 2. The binding is to be manufactured in different lengths to fit the different widths of matting, carpeting, 45 mats, &c.

The advantage of my binding is, that it will make the material to which it is attached lay smooth on the floor. It will keep the ends of the material from raveling and wearing out. 50 It will keep the material in place when laid on the floor. Its advantage over anything of the kind in use is, that by virtue of its being manufactured of rubber it can be rolled or bent in any direction, and will not break or 55 crack when the material to which it is attached is being handled for cleaning, moving, or any purpose whatever.

I claim—

60 The rubber binding, substantially as described, for the purpose specified, it consisting of a thin oblong piece of rubber, solid on one side and open on the other to admit the ends of the material to which it is to be attached, the open space being formed by flaps 65 that extend from the solid side and cover the ends of the material, all combined and arranged essentially as set forth.

CHAS. E. KNAPP.
